UNITED STATES PATENT OFFICE.

ADELBERT L. GOWER, OF JANEVILLE, WISCONSIN.

HEATING SYSTEM.

1,399,613.

Specification of Letters Patent. Patented Dec. 6, 1921.

Application filed March 29, 1920. Serial No. 369,629.

To all whom it may concern:

Be it known that I, ADELBERT L. GOWER, a citizen of the United States, and resident of Janesville, in the county of Rock and State 5 of Wisconsin, have invented certain new and useful Improvements in Heating Systems; and I do hereby declare that the following is a full, clear, and exact description thereof.

My invention relates to new and useful 10 improvement in heating apparatuses, and pertains particularly to one pipe steam heating systems.

In systems of this character it is frequently 15 difficult to cause the water of condensation to return to the boiler owing to back pressure, the presence of steam in the return pipe line and other causes. My invention therefore has for its particular object to overcome 20 these difficulties and permit the ready return to the boiler of the water of condensation.

With this general object in view, the invention resides in certain novel features of construction, combination and arrangement 25 of parts which will be hereinafter more particularly described and claimed and shown in the accompanying drawing, wherein the figure represents a portion of a steam heating system constructed in accordance with 30 the invention.

Referring to this illustration, it will be seen that this improved steam heating system includes a steam generator or boiler 1 in which the water is adapted to be retained at 35 the level x , a main steam supply pipe 2, one or more radiators 3 having a one way connection 4 with the supply pipe, a return pipe 5 and one or more condensation pipes 6 connecting the supply pipe and the return pipe. 40 It will be noticed that the return pipe 5 has its main portion substantially on the level of the water line x or slightly thereabove, although it enters the boiler 1 below the water line as at 7. In such a system as this steam 45 is designed to enter the radiator 3 to completely fill the same, steam being continuously supplied by the boiler to take the place of that which condenses; the water of condensation from the radiators enters the supply pipe 2 and flows therefrom down the pipe 6 to the return pipe 5.

However, the system with which my invention is designed to be used, is provided with one or more radiators 8 located adjacent to the boiler 1 between the normal level 55 of the steam supply pipe 2 and relatively ad-

jacent the level of the return pipe 5, these radiators being supplied with steam by an auxiliary supply pipe 9 which extends vertically from the main supply pipe 2 to the 60 bottom of the radiators. Water of condensation from the radiators 8 flows therefrom through an auxiliary condensation pipe 10 which indirectly connects with the return pipe 5.

If this pipe 10 is directly connected with the return pipe 5 there is a probability of steam entering the latter and setting up a back pressure which will prevent the water of condensation returning to the boiler. 70 Therefore to eliminate any likelihood of the return being interrupted, I have provided a water seal or trap between the auxiliary condensation pipe 10 and the return pipe 5. This arrangement preferably comprises a pipe 75 line in the form of a vertically positioned substantially rectangular loop 11, one end of which is a continuation of the vertical auxiliary condensation pipe 10, while the other end enters the return pipe 5 as at 12. The 80 top or highest point 13 of the loop 11 is a considerable distance above the water line x , but the lowest portion 14 thereof is below the bottom of the water in the boiler 1.

Thus, due to the water of condensation, the 85 loop 11 is completely filled with water, or the level of the same therein is above the water line x . However, even though the water in the loop is below the normal water line, any steam which tends to pass into the auxiliary condensation pipe 10 will be trapped and prevented from flowing into the return pipe 5. As a result of this construction the water of condensation readily flows from the return pipe into the boiler, and in fact, is 90 aided in some instances by the pressure of the steam in the auxiliary condensation pipe 10 pressing on the columns of water in the loop 11.

From the foregoing description taken in 100 connection with the accompanying drawing it will be seen that I have devised a very simply constructed arrangement for taking care of back pressures in one pipe steam heating systems, and especially in those in which 105 certain of the radiators are relatively close to the normal water level and adjacent to the steam generator. Various changes may be made in the form and proportions and in the general association of parts without departing from the principles or sacrificing any of 110 the advantages of the invention.

I claim:

1. In a steam heating system, a steam generator, a steam supply pipe, a radiator connected with the supply pipe relatively close to the generator, a return pipe connected with the base of the generator to return water of condensation thereto, a condensation pipe leading downwardly from the radiator, and a pipe loop having one end connected with the condensation pipe and the other end with the return pipe, the top of the loop being a relatively considerable distance above the water level of the generator, but below the bottom of said radiator, the bottom of the loop being below the lowest point of the return pipe.

2. In a steam heating system, a steam generator, a main steam supply pipe extending therefrom, an upper story radiator, a branch pipe leading from the main steam supply pipe to said radiator, a

second branch supply pipe connected with the main steam pipe and leading to a lower story, radiators connected with the last named branch pipe, a condensation pipe leading downwardly from said lower story radiators, a return pipe connected with the base of the generator to return water of condensation thereto, and a pipe loop having one end connected with the condensation pipe and the other end with the return pipe, the top of the loop being a relatively considerable distance above the water level of the generator, but below the bottom of the radiators in the lower story, the bottom of the loop being below the lowest point of the return pipe.

In testimony that I claim the foregoing I have hereunto set my hand at Milwaukee, in the county of Milwaukee, and State of Wisconsin.

ADELBERT L. GOWER.
